TABLE LIGHTER

Cecil B. Woofter, Newton, Iowa, assignor to
The Vernon Company
Newton, Iowa 50208

Filed Sept. 4, 1969, Ser. No. 19,003

Term of patent 14 years

Int. Cl. D27—05

U.S. Cl. D48—27

FIG. 1 is a perspective view of a table lighter embodying my new design.

FIG. 2 is a front elevational view of the table lighter on a reduced scale.

FIG. 3 is a side elevational view thereof.

FIG. 4 is a rear elevational view thereof.

FIG. 5 is a top plan view thereof.

The bottom of the lighter is flat and unornamented.

I claim:

The ornamental design for a table lighter, substantially as shown and described.
